UNITED STATES PATENT OFFICE.

ARTHUR E. ANAKIN, OF LONG BEACH, CALIFORNIA.

SASH BALANCE.

Application filed April 28, 1925, Serial No. 26,491.

To all whom it may concern:

Be it known that I, ARTHUR E. ANAKIN, citizen of the United States, residing at 950 American Avenue, Long Beach, in the 5 county of Los Angeles and State of California, have invented certain new and useful Improvements in a Sash Balance, of which the following is a specification.

This invention relates to sash balances and 10 has special reference to a spring sash balance.

One important object of the invention is to improve the general construction of devices of this character.

15 A second important object of the invention is to provide an improved form of spring sash balance wherein a simple and compact form of compression spring may be used in association with certain other 20 arrangements.

A third important object of the invention is to provide a form of sash balance employing a compression spring which is of such compact nature that it is economical 25 in construction and can be readily applied to a window without material changes in either the sash or frame.

With the above and other objects in view 30 as will be hereinafter apparent, the invention consists in general of certain novel details of construction and combinations of parts hereinafter fully described, illustrated in the accompanying drawings and specifically claimed.

35 In the accompanying drawings like characters of reference indicate like parts in the several views, and:

Figure 1 is a face view partly in section of a portion of a window and frame showing the balance in position.

40 Figure 2 is an enlarged view showing the parts of the balance in expanded position.

Figure 3 is a view similar to Figure 2 showing the parts of the balance in compressed position.

45 Figure 4 is a greatly enlarged vertical section through the balance.

In the form of the invention here illustrated there is provided a channel shaped casing resembling a box open at one side and this casing has side walls 10 and a back wall 11. Extending between the side walls, at the lower end of the casing is a pin 12. At 13 is a lower tubular member having its upper end open and its lower end provided with a closure 14 whereon is mounted a pair

of ears 15 through which the pin 12 passes. Supported between these ears on the pin 12 is a series of independently revoluble sheaves 16. At 17 is an upper tubular member which has its lower end telescopically engaged with the open end of the member 13 and is provided, at its upper end, with a closure 18 supporting a pair of spaced ears 19. In the ears 19 is mounted a pin 20 on which are arranged the independently revoluble sheaves 21.

Led around the sheaves 16 and 21 is a flexible strand in the form of a sash cord or wire and one end of this strand is fixed 70 to the casing as at 22. The remaining end of this strand is free for attachment to the side of a window frame 23 as at 24, the casing being fitted into a suitable mortise 75 formed in the side edge of the sash 26.

Under these conditions, the spring 27, which is interposed between the closed ends of the tubular members, is compressed upon the sash being moved down and expands as 80 the sash moves upwardly. Thus, by selecting a suitable size of spring, the sash can be perfectly balanced.

There has thus been provided a simple and efficient device of the kind described and for the purpose specified.

85 It is obvious that minor changes may be made in the form and construction of the invention without departing from the material spirit thereof. It is not, therefore, desired to confine the invention to the exact 90 form herein shown and described, but it is desired to include all such as properly come within the scope claimed.

Having thus described the invention, what 95 is claimed as new, is:

1. In a sash balance, a pair of telescopically arranged tubular members, sheave supports each carried by the outer end of a respective member, sets of sheaves each supported on a respective sheave support, a flexible strand led around said sheaves outside of said members and having one end fixed and the other end free for attachment to part of a window, and a compression spring housed in said tubular members and 100 urging the same apart.

105 2. In a sash balance, a channel shaped casing adapted to fit in the side of a window sash, a pin extending from side to side of said casing adjacent one end thereof, 110 a tubular member having one end closed and provided with a pair of ears mounted

on said pin, a series of independently revoluble sheaves mounted on said pin between said ears, a second tubular member having one end telescopically engaged on the free end of the first tubular member and having its other end closed and provided with a pair of spaced ears, said member being normally housed in said casing, a pin carried by the last mentioned ears, a

series of independently revoluble sheaves 10 mounted on the second pin, and a spring in said tubular members urging the same apart, a flexible strand led around said sheaves and having one end fixed and its other end free for attachment to a window 15 frame.

In testimony whereof I affix my signature.
ARTHUR E. ANAKIN.
